UNITED STATES PATENT OFFICE.

HERMAN KOLLMAR, OF NEWARK, NEW JERSEY, ASSIGNOR TO BURSTOW, KOLLMAR & CO.,
OF NEWARK, NEW JERSEY, A FIRM.

DESIGN FOR A HEAD FOR FOBS, BROOCHES, PINS, OR SIMILAR ARTICLES.

No. 39,259.

Specification for Design.

Patented April 14, 1908.

Application filed February 6, 1908. Serial No. 414,659. Term of patent $3\frac{1}{2}$ years.

To all whom it may concern:

Be it known that I, HERMAN KOLLMAR, a citizen of the United States, residing at Newark, in the county of Essex and State of New Jersey, have invented a new, original, and ornamental Design for an Ornamental Head for Brooches, Lockets, Pins, or Similar Articles, of which the following is a specification, reference being had to the accompanying drawing, forming part thereof.

What I claim is:—

The ornamental design for a head for fobs, brooches, pins or similar articles, as shown.

HERMAN KOLLMAR.
